UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed August 22, 1928. Serial No. 301,380.

My invention relates to mining machines, and more particularly to air operated mining machines.

An object of my invention is to provide an improved mining machine. Another object of my invention is to provide an improved mining machine of the air driven type having improved motive fluid supply connections. Other objects and advantages of my invention 10 will hereinafter subsequently appear.

In the accompanying drawings, in which one illustrative embodiment of my invention is disclosed,

Fig. 1 is a plan view of a mining machine 15 arranged in accordance with the illustrative embodiment of the invention.

Fig. 2 is a side elevation thereof.

Fig. 3 is a front end elevation thereof.

Fig. 4 is a detail cross section on the line 20 4—4 of Fig. 1.

Referring to the drawings, a mining machine 1 of the air operated type is shown cutting along a working face 2, the machine having its cutter bar 3 extending beneath the 25 coal as it moves in a left to right direction in Fig. 1. An air supply pipe 4 is provided at the forward end of the machine, and the supply of fluid through this pipe is controlled by a suitable hand wheel 5 controlling valve 30 mechanism not shown.

The movement of the machine being toward the right in Fig. 1, it is obviously desirable to avoid the making of an air connection by means of hose directly to the supply pipe 4, 35 for there would be danger of the machine's running over the hose and of the hose getting in the way of the machine runner. Accordingly I have provided a pipe connection 6 leading to an elbow 7, one of whose branches 40 extends vertically upward, and have arranged a hanger 8 above the elbow to guide and provide a journal for a vertically extending pipe 9. A flat conduit 10 is connected at one end to the upper end of the vertical pipe 9, 45 while at its other end the conduit 10 is provided with a depending air supply connection 11. As it is important that the overall height of the machine be kept low, the conduit 10 is made quite wide as indicated in Fig. 4 50 and very thin from top to bottom.

As the machine 1 may cut in either direction along a given face, that is, with either side of the machine next to the face, it is very desirable to provide for the attachment of the air supply in each case at the side of the machine remote from the face. Therefore provision is made to permit the disposition of the conduit 10 in different relations to the machine frame. The conduit may obviously 55 swivel about the axis of the pipe 9, and to permit its being held in different positions ears 12 are formed on opposite sides of it. Each of the ears is traversed by a hole 13 whose upper end is surrounded by a recess 10 to receive the head of a bolt, the holes 13 being 60 oval in form to permit the accommodation of screws in different relative positions. The top of the rear end of the machine 1 has a cover member 15 which is held in position by machine screws 16, and a machine screw 16 65 may be removed at either side of the machine and then reinserted in the hole 13 in one of the ears 12 for the purpose of locking the conduit in proper position. Similarly, screws 17 holding in position a smaller plate 18 may 70 be used in conjunction with the hole 13 in the other of the ears. By arranging the conduit with its air supply end remote from the face, the air supply hose is kept from so much wear 75 and more conveniently located. The air connection 11 is maintained within the transverse limits of the machine in either position 80 thereof.

From the foregoing description it will be 85 evident that I have provided a very simple method of enabling the supply of pressure fluid to be delivered at the rear end of an air operated mining machine without materially increasing the height thereof, and that this 90 mechanism permits the connection to be made in the most advantageous position irrespective of which side of the machine is next to the working face.

While I have in this application specifically 95 described one form which my invention may assume in practice, it will be understood that this form of the same is shown for purposes of illustration and that the invention may be modified and embodied in various other forms 100

without departing from its spirit or the scope of the appended claims.

What I claim as new and desire to secure by Letters Patent is:

- 5 1. The combination with a kerf cutting mining machine having kerf cutting mechanism, a fluid actuated driving motor therefor and a fluid supply connection for said motor at one end of the machine, of a supplemental fluid supply connection having communication with said first mentioned fluid supply connection and pivotally connected at one end at said end of the machine and extending along the top and outside thereof to the other 10 end of the machine and swingable into a plurality of positions relative to the machine, and means for holding said supplemental fluid supply connection in its different adjusted positions in each of which the same lies within the lateral limits of the machine but with its end at the end of the machine remote from its pivot adjacent one of said lateral limits.
- 15 2. The combination with a pressure fluid operated kerf cutting mining machine including a low compact machine frame having a plane top exterior surface, kerf cutting mechanism, a fluid actuated motor for driving said kerf cutting mechanism and a fluid supply connection for said motor at one end of the machine, of means for conducting pressure fluid from the other end of the machine to said fluid supply connections including a rigid fluid conduit member extending between the ends of the machine along the top and outside of the machine frame and lying substantially against the top plane exterior surface of the machine frame.
- 20 3. The combination with a pressure fluid operated kerf cutting mining machine having a plane top exterior surface, kerf cutting mechanism, a fluid actuated motor for driving said kerf cutting mechanism and a fluid supply connection for said motor at one end of the machine, of means for conducting pressure fluid from the other end of the machine to said fluid supply connections including a rigid fluid conduit member extending between the ends of the machine along the top and outside of the machine frame and lying substantially against the top plane exterior surface of the machine frame and disposable in different positions with respect thereto.
- 25 4. The combination with a pressure fluid operated kerf cutting mining machine including a low compact machine frame having a plane top exterior surface, kerf cutting mechanism, a fluid actuated motor for driving said kerf cutting mechanism and a fluid supply connection for said motor at one end of the machine, of means for conducting pressure fluid from the other end of the machine to said fluid supply connection including a rigid fluid conduit member adjustably connected to said supply connection and ex-
- 30 tending between the ends of the machine along the top and outside of the machine frame and lying substantially against the top plane exterior surface of the machine frame and disposable in different positions with respect thereto.
- 35 5. The combination with a pressure fluid operated mining machine including a low compact machine frame having a plane top surface and a fluid supply connection at one end of the machine, of means for conducting pressure fluid from the opposite end of the machine to said fluid supply connection including a conduit member extending along the top of and lying substantially against the top plane surface of the machine and disposable in different positions with respect thereto, said member having a fluid tight swivel connection at one end of the machine about which said member is swingable into said different positions, and means for securing said member in said different positions.
- 40 6. The combination with a pressure fluid operated kerf cutting mining machine including a low compact machine frame having a plane top exterior surface, kerf cutting mechanism, a fluid actuated motor for driving said kerf cutting mechanism and a fluid supply connection for said motor at one end of the machine, of means for conducting pressure fluid from the other end of the machine to said fluid supply connection including a rigid fluid conduit member substantially rectangular in cross-section extending between the ends of the machine along the top and outside of the machine frame and lying substantially against the plane top exterior surface of the machine frame.
- 45 7. The combination with a longwall pressure fluid operated kerf cutting mining machine having a low compact frame slidable on its bottom over the mine bottom, kerf cutting mechanism, a fluid actuated driving motor for said kerf cutting mechanism and a fluid supply connection for said motor at one end of the machine, of means for conducting pressure fluid from the opposite end of the machine to said supply connection including a rigid fluid conduit member extending along the top and outside of the machine frame and lying substantially against the top exterior surface of said frame and extending beyond the ends thereof, and a fluid inlet connection on said conduit member at the end thereof opposite from said first mentioned supply connection.
- 50 8. The combination with a longwall pressure fluid operated mining machine having a low compact frame slidable on its bottom over the mine bottom and a fluid supply connection at one end thereof, of means for conducting pressure fluid from the opposite end of said machine to said supply connection including a conduit member lying substantially

- against the top surface of said frame and extending along the top and beyond the ends thereof, and a fluid connection on said conduit member at the end thereof opposite from said first mentioned supply connection, said conduit member having a fluid tight swivel connection at one end thereof about which said member is swingable into different positions relative to said machine frame.
9. The combination with a pressure fluid operated kerf cutting mining machine adapted selectively to cut in opposite directions on opposed coal faces and having kerf cutting mechanism, a fluid actuated driving motor therefor and a fluid supply connection for said motor, of means for conducting pressure fluid to said fluid supply connection including a rigid fluid conduit member connected to said supply connection and having its inlet adjustable to positions at either side of the machine so that irrespective of the direction of cutting the fluid inlet is located at the side of the machine away from the coal face.
10. The combination with a pressure fluid operated kerf cutting mining machine adapted selectively to cut in opposite directions on opposed coal faces and having kerf cutting mechanism, a fluid actuated driving motor therefor and a fluid supply connection for said motor, of means for conducting pressure fluid to said fluid supply connection including a rigid fluid conduit member having a swiveled connection with said fluid supply connection and swingable to positions wherein its inlet is disposed at the side of the machine away from the coal face irrespective of the direction of cutting.
11. The combination with a pressure fluid operated kerf cutting mining machine adapted selectively to cut in opposite directions on opposed coal faces and having kerf cutting mechanism, a fluid actuated driving motor therefor and a fluid supply connection for said motor, of means for conducting pressure fluid from said fluid supply connection including a rigid fluid conduit member lying substantially against and extending over the top of the machine between the ends of the latter and connected to said supply connection and having its inlet adjustable to positions at either side of the machine so that irrespective of the direction of cutting said fluid inlet is located at the side of the machine away from the coal face.
12. The combination with a pressure fluid operated kerf cutting mining machine adapted selectively to cut in opposite directions on opposed coal faces and having kerf cutting mechanism, a fluid actuated driving motor therefor and a fluid supply connection for said motor, of means for conducting pressure fluid from said fluid supply connection including a rigid fluid conduit member lying substantially against and extending over the top of the machine between the ends of the

latter and having a swiveled connection with said fluid supply connection and swingable to positions wherein its inlet is disposed at the side of the machine away from the coal face irrespective of the direction of cutting.

In testimony whereof I affix my signature.

MORRIS P. HOLMES.
